UNITED STATES PATENT OFFICE.

JOSEPH STANSBURY JONES, OF NEW YORK, N. Y.

ELECTRIC SWITCH.

1,217,114.

Specification of Letters Patent. Patented Feb. 20, 1917.

Application filed September 23, 1915. Serial No. 52,169.

To all whom it may concern:

Be it known that I, JOSEPH STANSBURY JONES, a citizen of the United States, residing at New York city, in the county of New

5 York and State of New York, have invented new and useful Improvements in Electric Switches, of which the following is a specification.

This invention relates to electric switches, 10 and while features of the invention may be applicable to switches of many kinds, the invention is particularly applicable to the type of switch known as a snap switch.

Switches of this type embody fixed contacts and rotary contacts. When the handle of the switch is turned through an angle, this movement releases the rotary member of the switch and the spring of the switch moves the rotary member forward and locks 20 it in a new position, usually the on-and-off positions alternate.

A principal object of my invention is to provide a simple and efficient construction for the rotary switch member affording simple means for supporting the contact member. If the switch comprises more than one rotary contact member, my invention affords simple means for effectively carrying and insulating the rotary contact members.

30 A further object of the invention is to construct the rotary switch member in such a way that the body of the same may be readily molded of insulating material, and the parts carried by it are so constructed that 35 the body may be molded around them or in engagement with them so as to hold them rigidly in or on the insulating body.

A further object of the invention is to simplify and improve the construction of 40 the movable contacts and particularly as to the method of supporting the same at the binding posts; and my improvements also extend to the construction of the binding posts themselves.

45 Further objects of the invention will appear more fully hereinafter.

The invention consists in the general combination of parts and details hereinafter described, all of which contribute to produce an efficient electric switch.

A preferred embodiment of the invention

is described in the following specification, while the broad scope of the invention is pointed out in the appended claims.

In the drawing,

Figure 1 is a vertical section through a switch embodying my invention.

Fig. 2 is a plan of the switch upon a reduced scale.

Fig. 3 is a cross-section through the switch taken about on the line 3—3 of Fig. 1.

Fig. 4 is a bottom plan of the rotary switch member removed from the switch, certain parts being shown in cross-section. The view includes contiguous parts.

Fig. 5 is a bottom plan of a cam plate removed from the switch.

Fig. 6 is a vertical section through the rotary switch member, and also indicating the manner in which one of the movable contacts cooperates with the fixed contacts.

Fig. 7 is a perspective of the rotary switch member removed from the switch and showing the lower end thereof.

Fig. 8 is a perspective of the spindle of the switch and showing details of the releasing device which cooperates with the other parts in effecting the advancing or rotary movement of the switch.

Fig. 9 is a plan of the central portion of the rotary switch member showing details.

Although I have illustrated and described in the inclosed specification my improvements as applied to a rotary switch, it is understood that many of the features of the invention may be applied to switches generally, and that the switch described is set forth merely by way of example.

The snap switch illustrated comprises a case 10 which may be of circular form as shown, said case being provided with a suitable screw cap or cover 11 with a stuffing box 12 through which passes the switch spindle 13, said spindle being provided with a handle 14, preferably in the form of an indicating arrow, see Fig. 2. This handle may be attached to the spindle by screw threads 15, but these threads are of such a character that the handle screws onto the spindle in the same direction in which it is rotated to operate the switch; for example, clockwise or in the direction of the arrow indicated in

Fig. 2. This prevents the handle from coming unscrewed in operating the switch.

In the bottom of the switch case 10 there is provided an insulating block 16 which is held fixed in the case in any suitable manner. This block is preferably provided with a central recess 17 at its under side, and the upper wall of which is provided with a bushing 18 which forms a bearing for the lower end of the spindle 13, the spindle being held against withdrawal by any suitable means such as the split pin and washer 19. The upper end of the bushing 18 has a thread connection with a cam plate 20, see Fig. 5, which is instrumental in locking the switch in its different positions. For this purpose the cam plate is preferably provided with a plurality of recesses or notches 21 in its edge between which the periphery of the plate is formed with spiral or cam edges 22. This cam plate is held in a fixed position by means of a small screw 23 or any other suitable means.

Cooperating with the cam plate there is provided a cam 24, see Fig. 8, said cam being in the form of a plate with a circular opening 25 therein which receives an eccentric 26 which is rigidly mounted on the spindle 13. The cam plate 24 has a short substantially radial arm 27 having a laterally projecting dog 28 which is adapted to engage successively in the notches 21 as the switch is rotated to its successive positions.

Referring to Fig. 4 which shows the switch viewed from the bottom, when the spindle 13 is rotated in the direction indicated by the arrow in Fig. 4, the eccentric 26 moves the cam arm 27 outwardly so as to release the dog 28 from the notch, and the spring then drives the cam forwardly around the edge of the cam plate and locks it in the notch which is next in advance. In the switch illustrated, the rotary movement of the cam 24 is imparted to the rotary switch member 29, see Fig. 7, and this is preferably accomplished through the medium of a member or cam rack 30 which is in the form of a plate having two lugs 31 between which the arm 27 lies. From this arrangement evidently when the cam 24 rotates forward, it carries with it the cam rack 30.

Referring particularly to Fig. 1, I prefer to form the cam rack 30 with a central opening which receives the lower end of a bushing or tubular sleeve 32, said sleeve preferably having a circumferential shoulder 33 which seats on the upper side of the rack. The spring 34 is disposed in a helical coil around the sleeve 32 and its lower end has a longitudinal extension 32^a which is received in engaging means such as an opening 35 formed in the rack, see Figs. 6 and 7. The upper end of the spring has an extension 36 which may be secured at any point around the periphery of a collar 37 which is rigidly

secured to the spindle and which collar has a plurality of inclined equidistant notches 38 in order to receive the extension or shank 36 of the spring. Evidently, this arrangement enables the tension of the spring to be nicely adjusted.

The rotary switch member 29 preferably has a body 39 of insulation which is preferably formed of any suitable composition such as fiber, which can be molded. This enables me to mold this body around the movable switch member and it also enables me to mold the body in such a way that it holds the plate 30 in place. In the present instance, the switch has two rotary conductive parts or contacts 40 and 41 which are disposed in different planes transversely to the axis of the spindle. This insulating body 39 then operates to hold the contacts 40 and 41 and the member 30 in a fixed relation to each other, and it also operates to insulate them. The contact members 40 and 41 preferably operate as bridge contacts to connect two diametrically opposite terminals in the case, and for this purpose they are preferably formed each with a ring-shaped body 42 and fan-tail arms or blades 43 which project outwardly. When they are molded in the insulating body 39, the ring bodies of the contacts are completely embedded in the insulation 39 and the blades 43 are the only parts of the movable contacts which are in sight, and they may project in some such manner as illustrated in Fig. 7. The two contacts are also preferably disposed in different angular positions with respect to the axis of rotation.

I prefer to provide guiding means to assist in placing the spring 34 in position. For this purpose I prefer to bend the extension 32^a outwardly slightly and form the bore 39^a of the insulating body 39 (see Fig. 9) with a longitudinal guide groove, which aligns with the opening 35 and guides the extension 32^a into the opening 35.

In one position of the switch, the switch contact 40 may connect two diametrically opposite contacts 44^a and 44^b, while two intermediate diametrically opposite contacts 45^a and 45^b are connected by the contact 41.

As one end of the spring 34 is anchored rigidly on the spindle 13 at the spring collar 37, it of course tends to rotate the spindle in an opposite direction to that indicated by the arrow in Fig. 3. The spindle, however, is locked against rotation by means of the lug 46 engaging the edge of cam 24.

The fixed contacts 44^a and 44^b and 45^a and 45^b are preferably specially constructed to cooperate with the blades or wings 43 and also to facilitate the mounting of the fixed contacts in their binding posts 48. These binding posts 48 are preferably four in number and disposed diametrically opposite to each other. They are held in position by

suitable screws 49 passing up through the insulating block 16. In order to reduce the height of the case and to bring the lower switch contact 40 as near as possible to the insulating block 16, I prefer to provide a recess 50 in the upper face of the insulating block which receives the lower end of the body 39 of the rotary switch member and its contiguous parts.

10 In order to insure that the member 30 will be securely held in the body 39 when it is molded, I prefer to form the plate or member 30 with projections 51 on its edges, see Fig. 6. When the body 39 is molded it extends on the outer side of these projections, and, of course, prevents the plate from being pulled out of the insulating body. The binding posts 48 are preferably formed of a relatively soft brass and they are preferably 15 provided on their inner sides with deep concave recesses or throats 52, and in these throats I form transverse saw cuts or flat grooves 53. These grooves or cuts 53 receive the inner ends of the fixed contact members 20 44^a which are disposed in pairs as shown. These contacts may be sweated in position or pinned to secure them. The inner ends of these fixed contacts are preferably bifurcated for which purpose they are formed with a 25 central slot 54, which renders the contacts flexible. The fixed contacts are preferably formed with transverse bows or bends 55 which cause them to yield resiliently when the moving contact wings 43 come into place 30 between them. The forward edges, that is, the edges of the contact plates which receive the wings 43 are preferably formed with outwardly bent lips 56 which facilitate the guiding of the wings 43 into place. In 35 order to hold the leading-in wires 57 securely in the binding posts, I prefer to provide each binding post with a binding screw 58 having a swiveled collar 59 at its lower end, which collar is received in an opening 40 enlarged or gap 60 which is cut through the binding post. This enlarged opening receives the swiveled collar. When the wire 57 is put in place under the screw, the swiveled collar seats on the wire without 45 turning and the rotation of the screw 58 clamps it firmly against the wire. When properly clamped, the set screw is secured by means of a lock nut 61 which seats against the upper end of the post.

50 The case 10 is preferably provided at diametrically opposite points with bosses 62 to receive the conduits or pipes carrying the wires, one wire being carried toward one contact, for instance, 45^a, and the other to 55 the contact 45^b.

It is understood that the embodiment of the invention set forth herein is only one of the many embodiments or forms the invention may take, and I do not wish to be

limited in the practice of the invention nor 65 in my claims to the particular embodiment set forth. And I may use any feature of my invention without the other features.

What I claim is:

1. In a switch, a unitary contact-carrying 70 member adapted to be rotated, said member comprising conductive contact parts disposed on spaced-apart planes intersecting the axis of the member, and a body of insulation in which each of said contact parts is 75 secured, said body insulating the parts one from another and being molded about the parts to lock them against movement relative to the body and to each other, whereby said parts may be held to rotate in unison 80 without the presence of metallic members intersecting the planes of such parts within the body.

2. In a switch and in combination, a unitary contact-carrying member adapted to be rotated, said member including a conductive contact part, and a part operative in the member-moving operation, means coöperating with said last named part to effect the rotation of said member, said rotary member 85 having a body of insulation molded to unite said parts in the unitary structure and to form a lock therefor to prevent relative movement between the parts and such body, whereby said parts will be fixedly positioned 90 within the unit without the presence of metallic members intersecting the several planes of such parts within the body, and fixed contacts coöperating with the conductive contact part.

3. In a rotary snap-switch, in combination, a rotary switch member having a conductive part and having another part formed of metal to facilitate the rotation of said rotary switch member, means coöperating with said last named part to effect the rotation of said rotary switch member, said rotary member having a body of insulation molded about said conductive part and holding the same fixed in the insulation, said other part disposed at the end of said body having projections molded into said body to retain the same in said body and having means projecting outwardly to enable said body to be rotated, and fixed contacts co- 100 operating with said conductive part.

4. In a rotary snap-switch, in combination, a rotary switch member having a conductive contact part, said rotary member having a body of insulation molded about said conductive part to hold the same in place, a cam rack disposed at the end of said body having projections about which said body is molded and operating to retain said 105 rack fixed in said body, a cam guided on said cam rack, an eccentric for actuating said cam, a cam-plate coöperating with said cam, a stem for rotating said eccentric to

- release said cam from said cam-plate, a spring for normally holding said cam locked on said cam-plate, and fixed contacts co-operating with said conductive contact part.
- 5 5. A switch member having engaging means in one end thereof for engaging one end of a spring, said member further having a bore to receive the spring, with a longitudinal guide groove in alinement with said 10 engaging means, and a spring received in said bore having an extension adapted to be guided by said guide groove into engagement with said engaging means when the spring is placed in position.
- 15 6. A rotary switch member having a molded insulating body and a contact blade carried thereby, said insulating body having a bore and having a plate molded in said body at the end of said bore, said plate having 20 an opening therein to receive the end of a spring, said bore having a guide groove therein alining with said opening, and a spring to actuate said rotary member mounted in said bore and having an extension adapted to be guided by said guide 25 groove when the spring is placed in the bore to guide the end of the spring into said opening.
7. In a rotary snap-switch, the combination of a rotary switch member, having a conductive contact part, said rotary member having a body of insulation molded about said conductive part and holding the same fixed in the insulation, a metallic part embedded in the end of said insulating body 30 and held fixed by the insulation, the said metallic member having outwardly projecting means for co-operating to effect the rotation of said rotary switch member, said body and insulation having a bore therein, 35 a spring lying in said bore engaging said metallic member, and means co-operating with said spring and said metallic member to effect the rotation of said rotary member.
- In testimony whereof I have hereunto set my hand in presence of two subscribing witnesses:

JOSEPH STANSBURY JONES.
